ATTYS.

UNITED STATES PATENT OFFICE.

LOUIS A. SCHMIDT, OF BROOKLYN, NEW YORK, ASSIGNOR TO R. HOE & CO., INC., OF NEW YORK, N. Y., A CORPORATION OF NEW YORK.

PLATE CLAMP.

Application filed June 6, 1927. Serial No. 196,705.

This invention relates to certain improvements in plate clamps.

In printing practice, where stereotype or similar plates are employed, the plates are clamped on the plate supports by means of 5 clips which lap over the edges of the plates and by which the plates are clamped against a suitable abutment, so that they are rigidly held in position during the printing operation. In printing certain products, as for 10 instance newspapers, the printing is usually effected on rotary machines in which the plate supports are cylinders capacitated to carry a number of plates wide, that is, widthwise of 15 the cylinder. Between two adjacent plates are formed what are usually termed margin spaces, that is, spaces in which no printing is effected, so that the desired margin between the pages is produced, and at times it is desirable 20 to provide margin spaces of different widths. It also frequently happens that different width products are to be produced on the cylinder and provision must be made for adjusting the clamps accordingly, and it may often happen that a double wide page is required, so that certain of the clamps have to 25 be removed from the cylinder. The various changes can be quickly and effectively made by the rotary clamp having differently 30 formed clamping surfaces, either of which upon the rotation of the clamp may be brought toward a plate on the support, such a clamp being described and claimed in my prior Patent No. 1,450,609, dated April 3, 1923.

35 It frequently happens in printing practice, however, that the printing plates are cast in some instances from wet mats and in other instances from dry mats. When a wet mat is used, after the mat is pressed into the form, it is dried in a heated press while still in contact with the form, and there is practically no shrinkage; hence the plate cast from a wet mat is substantially the same size as the form from which the mat was made. In the use of 40 dry mats, however, they are removed from the form immediately after the impression is made and the slight amount of moisture which they contain is driven off by placing the mats in a scorching. A slight shrinkage occurs during the scorching and the plate cast from dry mats is therefore smaller than the form. At 45 times advantage is taken of this shrinkage and a smaller width web or sheet used when printing from dry mats. On account of the 50 smaller size of the plate, however, a change in

the position of the plate clamps which hold the plate on the plate support is necessary.

It is the especial object of the present invention to improve the rotary clamp of my prior patent so that this clamp can be readily 60 and quickly adjusted sidewise to compensate for these slight differences in the widthwise dimensions of the plates.

With this and other objects not specifically referred to in view, the invention consists in 65 certain novel parts, arrangements and combinations which will be described in connection with the accompanying drawings and the novel features pointed out in the claims hereunto annexed.

In these drawings,—

Figure 1 is a partly broken away sectional view of a part of a plate cylinder showing the improved clamp as employed with two plates of a certain width;

Figure 2 is a similar view showing the relative position of the clamp when used for clamping two narrower plates;

Figure 3 is a similar view showing the position of the parts when clamping a double 80 wide plate;

Figure 4 is a detail sectional view showing the position of the clamp adjusted to compensate for slight variations in the width of the plates of Figures 1 and 2, and

Figure 5 is a sectional end view, partly broken away, showing certain details of construction.

Referring now to these drawings, the invention has been illustrated as employed with a plate support to carry two or more plates wide, three such plates, indicated at 1, 2 and 3 in Figures 1 and 2, being shown, these plates having the usual bevelled edges 4. In the particular construction illustrated, the plate support is a cylinder, indicated at 5, but it will be understood as to certain of its features the invention is capacitated for use in structures in which plate supports other than cylinders are employed.

In accordance with the invention, there is provided an improved plate clamp which is provided with two clamping surfaces arranged on different sides of the clamp, these surfaces in the particular clamp here shown being in offset relation to each other, and there being a plain side for use with the double wide plate shown in Figure 3. This clamp is so arranged that it may be manipulated to bring either the plain side or either of the plate

holding clips into operative position with respect to the surface of the cylinder and, preferably, this will be effected by a rotary movement, so that by turning the clamp by means of a suitable tool the desired side may be brought into position, such a clamp providing means for quickly and effectively clamping plates varying considerably in width. The improved clamp will also include means whereby small differences in the widths of the plates may be compensated for and, preferably, this will be effected by a rotary movement of the clamp, so that the adjustments can be quickly and easily made and without the necessity of any special adjusting devices.

In the particular construction illustrated, there is provided a clamp, one side of which, as 6, is provided with a clamping surface 7 provided with undercut sides 8 corresponding to the bevelled sides of the plate. Another side of this clamp, as 9, is provided with a clamp 10, also having undercut sides 11 for engaging the bevelled edges 4 of the plate. The clamp is also formed on a third side 12 with a flat or plain surface. It will be observed in the particular clamp illustrated in the present case that the surfaces 7 and 10 are in offset relation to each other, the clamp being wide enough so that this offsetting produces the required variation in spacing of the plates, as for instance a column width.

Where both the plates, as for instance, the plates 1 and 2 in Figure 1, or the plates 13, 14 of Figure 2 are of the same width, the rotation of the clamp properly positions the clamping surfaces with respect to the edges of the plates. Where the plates are of slightly different width, however, due to the use of dry mat or a wet mat in making them, the clamping surfaces would not be in proper position for clamping the edges of the plate. Means, therefore, are provided by the present invention, as before stated, whereby the clamp may be given a sidewise movement to compensate for this difference in the plate widths and, in the best constructions, this is effected by a rotary movement of the clamp itself.

While the particular construction for mounting the clamp in the cylinder so that this may be effected may be somewhat varied, in the particular construction illustrated the cylinder is recessed to receive a clamp carrying case or box 15 in which is rigidly supported a stud 16 having a threaded end 17. The threaded end of this stud is threaded into the clamp, and the clamp carrying case or box is, as shown, made somewhat longer than the clamp. It will be observed that by rotating the clamp one turn the clamp will be given a sidewise movement in the box and the clamp will be moved the distance corresponding to one thread, as for instance the difference between the position shown in Figures 1 and 4. Thus the clamping surface 4 of Figures 1 and

4 is in clamping relation with the plates, but has been moved sidewise a slight distance so as to compensate for the slight difference in the width of the plates.

The outside plates 1 and 13 are clamped in the usual manner by means of clamping blocks 18 operated by the usual screw rod 19, and the inside edge of the inner plates may be clamped against a clamp 22, which if desired may be movable, being mounted on a screw rod 23 operated by a gear 24. If desired, a spring pin 20, see Figure 4, may be provided for holding the clamp in adjusted position; this pin taking into a hole 21 formed in the walls of the box or case 15.

With the construction shown and described, it will be seen that the clamps may be readily adjusted for clamping plates of widths varying a certain predetermined distance, as a column, and at the same time may be adjusted for clamping such plates where the plates vary slightly in width.

While the invention has been shown and described in its preferred form, it will be understood that certain variations may be made in the form of the clamping surfaces and in the arrangement of the clamping surfaces on the clamp and in other details shown and described without departing from the invention as defined in the appended claims.

What I claim is:

1. In a plate clamp, the combination of a plate support, a recess in the support, a rotary clamp in the recess having differently formed faces, either of which may be brought toward a plate on the support by rotating the clamp, and means for effecting a sidewise movement of the clamp in the recess to adjust it for slight differences in the width of a plate.

2. In a plate clamp, the combination of a plate support, a recess in the support, a rotary clamp in the recess having differently formed faces, either of which may be brought toward a plate on the support by rotating the clamp, and means whereby the rotation of the clamp effects a sidewise movement thereof to adjust the clamp for slight differences in the width of a plate.

3. In a plate clamp, the combination of a plate support, a recess in the support, a rotary clamp in the recess having differently formed faces, either of which may be brought toward a plate on the support by rotating the clamp, a recess in the support, a box in the recess longer than the clamp, and means whereby the clamp may be given a sidewise movement in the recess by its rotation.

4. In a plate clamp, the combination of a plate support, a recess in the support, a rotary clamp in the recess, and means whereby the rotation of the clamp effects a sidewise adjusting movement thereof.

5. In a plate clamp, the combination of a plate support, a recess in the support, a rotary

clamp in the recess, and a fixed threaded pivot on which the clamp is threaded.

6. In a plate clamp, the combination of a plate support, a recess in the support, a rotary clamp shorter than the recess mounted therein, and a fixed threaded pivot in the recess 5 on which the clamp is threaded.

7. In a plate clamp, the combination of a

plate support, a recess in the support, a box in the recess, a clamp block shorter than the box mounted therein, and a threaded rod 10 fixed against rotation in the box on which the clamp block is threaded.

In testimony whereof, I have hereunto set my hand.

LOUIS A. SCHMIDT.
